R. C. G. STAATS-OELS

SHOCK ABSORBER

Filed July 11, 1924

Fig.1.

Fig.2.

Inventor

RUDOLPH C. G. STAATS-OELS

By his Attorneys, Richards & Geier

UNITED STATES PATENT OFFICE.

RUDOLPH C. G. STAATS-OELS, OF BROOKLYN, NEW YORK.

SHOCK ABSORBER.

Application filed July 11, 1924. Serial No. 725,411.

To all whom it may concern:

Be it known that I, RUDOLPH C. G. STAATS-OELS, a citizen of the United States, residing at Brooklyn, county of Kings, and State of New York, have invented certain new and useful Improvements in Shock Absorbers, of which the following is a specification.

This invention relates generally to shock absorbers for automobiles, the invention having more particular reference to a shock absorber utilizing air compression.

The invention has for an object the provision of a novel and improved shock absorber of the piston and plunger type which operates by air compression, a further object of the invention relating to the increase of general cushioning effect by the use of a plurality of cylinders that telescope one into the other.

For further comprehension of the invention, and of the objects and advantages thereof, reference will be had to the following description and accompanying drawing, and to the appended claims in which the various novel features of the invention are more particularly set forth.

Fig. 1 of the drawing is a central vertical sectional view of my improved shock absorber.

Fig. 2 is a transverse sectional view thereof taken on the line 2—2 of Fig. 1.

Referring now to the drawing, the reference numerals 10, 11 and 12 designate three cylinders which are closed at the bottom by the bottom members 10', 11' and 12' respectively. These cylinders are open at their upper ends, the top cylinders 10 fitting into and forming a plunger in the intermediate cylinder 11, while the latter fits into the upper end of the lower cylinder 12 and forms a plunger in the latter. Fitting slidably in the top cylinder 10 is a plunger 14. This plunger 14 is formed on its upper end with an upwardly projecting ear 15, while the cylinder 12 has formed on the bottom thereof a downwardly projecting ear 16 these ears 15 and 16 forming the medium of attachment of the device to the body and axle of the automobile, and being here shown as provided with apertures 17 to receive fastening pins or bolts. It will be understood of course that any suitable provision may be made for attaching the plunger 14 and the cylinder 12 to the proper automobile parts. The plunger 14, and cylinders 10 and 11 have their upper halves of diminished di-

ameter, forming shoulders 20 that are adapted to be engaged by rings 21, 22 and 23 screwed into the respective cylinders 10, 11, and 12 to prevent longitudinal displacement of the various parts from one another.

Fixed at its lower end to the bottom 12' of the lower cylinder 12 is a tube 25 that extends upwardly through the bottoms of the other cylinders 10 and 11. This tube is surrounded by an exterior sleeve 26 which is of approximately the same length as the tube and which fits snugly in the apertures provided in the bottoms of the cylinders 10 and 11. The tube 25 and sleeve 26 are formed with rows of registering apertures 27 and 28 that are placed throughout the length of said sleeve and tube, these apertures constituting ports through which air passes into and out of the cylinders 10, 11, and 12. At its upper end, the tube sleeve 26 fits frictionally in a bushing 29 fitted into the lower end of a longitudinal passage 30 in the plunger 14, this passage accommodating the tube and sleeve when the parts move in a collapsing direction. Fixed at its ends to the sleeve 26 is a pin 31 that passes through short longitudinal slots 32 in the tube 25, the pin engaging the upper ends of the slots when the apertures 28 and 27 in the sleeve and tube are in registry with one another.

In the operation of my improved shock absorber, assuming the parts to be in the relative positions shown in the drawing, an initial downward movement of the plunger 14 will cause the sleeve 26 to move downward on the tube 25 until the pin 31 engages the lower ends of the slots 32, the friction between the sleeve 26 and bushing 29 being greater than that between the tube 25 and the sleeve. The ports leading from the various cylinders are thus immediately closed, and further downward movement of the plunger, or of the upper cylinders 10, 11, will cause the air in the various cylinders to be compressed. As soon as the recoil movement starts the sleeve 26 is moved upward to open the said ports, allowing the air to escape. By this means any recoil effect from the air is prevented, the device utilizing only the cushioning effect thereof as the springs of the automobile compress.

If desired I may vary the degree of air compression resulting in each cylinder as the downward movement of the parts occurs, which may be effected by slightly vary-

ing the positions of the openings in the lower parts of the sleeve so that the latter do not move entirely out of registry with the openings in the tube at any time.

5 Having thus described my invention, what I claim as new and desire to protect by Letters Patent of the United States is as follows:

- 10 1. A shock absorber including a cylinder, a plunger operable to vary atmospheric pressure therein, a valve device including an apertured tube secured at one end to said cylinder and communicating with the atmosphere, and an apertured sleeve movable with said plunger longitudinally of said tube to bring the apertures in the sleeve into and out of registry with those in said tube to open and shut off communication between said cylinder and the atmosphere.
- 20 2. A shock absorber including a cylinder, a plunger operable to vary atmospheric pressure therein, and a valve device including a tube and a sleeve each having apertures, one of the latter elements being movable relative to the other when the plunger is operated to bring the apertures in said elements into and out of registry.
- 30 3. A shock absorber including a plurality of telescoping cylinders, a plunger movable in one of said cylinders and operable by contact therewith to successively compress the air in the various cylinders, and a valve device including a tube and a sleeve each having apertures, one of the latter elements being movable relative to the other when the plunger is moved in one direction to bring the apertures in said elements out of

registry to close communication between said cylinders and the atmosphere.

4. A shock absorber for automobiles comprising a cylinder, a tube fixed at its lower end in the bottom of said cylinder and communicating with the atmosphere, a plunger, a sleeve surrounding said tube, said sleeve being frictionally engaged with said plunger, and co-operating means on said sleeve and tube arranged to permit of limited sliding movement of the sleeve on the tube, said sleeve and tube having apertures therein adapted to be moved into and out of registry by sliding movement of the sleeve on the tube.

5. A shock absorber for automobiles comprising a plurality of vertically disposed cylinders fitting telescopically into one another, a plunger fitting into the top cylinder, a tube fixed at its lower end in the bottom of the lower cylinder, a sleeve surrounding said tube, said sleeve and tube extending upward through the bottoms of the upper cylinders, said sleeve being frictionally engaged at its upper end with the said plunger, a pin fixed in said sleeve and passing through short vertical slots in the said tube to limit sliding movement of the sleeve on the tube, said sleeve and tube having rows of apertures spaced substantially throughout the length thereof, said apertures being adapted to be moved into and out of registry with one another by sliding movement of the sleeve on the tube.

In testimony whereof I have affixed my signature.

RUDOLPH C. G. STAATS-OELS.
